(57) **CLAIM**

The ornamental design for a rifle flagpole, as shown and described.

DESCRIPTION

FIG. 1 is a side perspective view of a rifle flagpole showing the hew design;

FIG. 2 is a left side view (in relation to the front elevational view) thereof;

FIG. 3 is a right side view (in relation to the front elevational view) thereof;

FIG. 4 is a top plan view thereof; and

FIG. 5 is a bottom plan view thereof.

FIG. 6 is a front elevational view thereof; and,

FIG. 7 is a rear perspective view thereof.

The broken lines in the drawings illustrate a portion of the rifle flagpole that forms no part of the claimed design.
